COMBINED HOISTING APPARATUS AND AUTOMATIC COVER STRUCTURE THEREFOR

David A. Wallace, Grosse Pointe Farms, Mich.

Application April 20, 1949, Serial No. 88,652

10 Claims. (Cl. 254—89)

1

This invention relates to improved hoisting apparatus.

More particularly the invention pertains to improved cover mechanism for vehicle hoisting apparatus such as that set forth in my pending applications, Serial Nos. 15,827, 34,772 and 58,219.

One of the main objects of the invention is to provide fully automatic, self acting cover mechanism of this kind which is adapted to substantially completely cover the recess or chamber in a floor or other structure in which the boom members and operating means of hoisting apparatus is received when the hoisting apparatus is in its lower position.

Another object of the invention is to provide cover mechanism of this kind for such hoisting apparatus receiving recess or compartment which is automatically shifted from closed to open position during raising and lowering, respectively, of the boom members and which is returned to closed position when the boom members reach their uppermost and lower positions, respectively, without requiring manipulation, adjustment or other attention of the operator.

A further object of the invention is to provide cover mechanism of this kind which can be applied to the recesses in which are received multiple unit hoisting apparatus of the type in which the respective hoisting units can be variably positioned to accommodate lifting of vehicles of diverse lengths.

A still further object of the invention is to provide a plurality of pivotally connected cover sections in cover mechanism of this kind which are shiftable relative to each other by the raising and lower movements of the respective parts of the housing apparatus and in such timed relationship with respect to movements thereof as to avoid obstructing interferences, free falling of cover sections from substantial heights and noisy operation.

An additional object of the invention is to provide cover mechanism of this kind which performs its intended purpose while the hoisting units of apparatus including a pair of such units are spaced at diverse distances from each other to accommodate lifting of vehicles of different lengths.

An illustrative embodiment of the invention is shown in the accompanying drawings, in which:

Fig. 1 is a perspective view of hoisting apparatus provided with cover mechanism embodying the invention showing portions of the cover structure removed to disclose the underlying hoisting

2

apparatus construction and illustrating the hoisting apparatus in its elevated position.

Fig. 2 is a fragmentary, longitudinal, vertical sectional view taken on line 2—2 of Fig. 1.

Fig. 3 is a fragmentary plan of the central portion of the hoisting apparatus shown in longitudinal vertical section in Fig. 2.

Fig. 4 is a transverse, vertical sectional view taken on line 4—4 of Fig. 3.

Fig. 5 is a transverse, vertical sectional view taken on line 5—5 of Fig. 1.

Fig. 6 is a perspective view of hoisting apparatus provided with cover mechanism embodying the invention and showing the hoisting apparatus in its fully lowered condition.

Fig. 7 is a fragmentary, perspective view of the left end portion of the hoisting apparatus shown in Fig. 6 illustrating portions of the cover in their initial state of opening and last stages of closing movements which correspond with the first increment of raising movement and last stage of lowering movement, respectively, of the hoisting apparatus.

Figs. 8, 9, 10, 11 and 12, show that portion of the hoisting apparatus, and its cover mechanism, illustrated in Fig. 7, in successive stages of its upward movement, respectively, and which views, in reverse order, illustrate the positions of the cover mechanism at successive stages of lowering movement of the hoisting apparatus.

Fig. 13 is a fragmentary perspective view of the right end portion of the hoisting apparatus shown in Fig. 6, illustrating the cover removed to disclose the underlying construction.

Fig. 14 is a fragmentary perspective view of the left end portion of the hoisting apparatus illustrated in Fig. 6, showing the cover member of the apparatus in fully closed position.

Fig. 15 is a fragmentary side elevational view showing one of the hoisting units of the apparatus illustrated in Fig. 1, in a position to which it is bodily shifted to obtain a favorable initial mechanical advantage during the first stages of operation of the hoisting unit from its lowermost position.

The hoisting apparatus of this application includes a pair of hoisting units and is generally similar to that disclosed in my copending application, Serial No. 58,216, filed November 4, 1948 and in some respects the apparatus is similar to the hoisting apparatus shown in my copending application, Serial No. 34,772, filed June 23, 1948. In this application, the hoisting apparatus is provided with an automatic, self-operating cover structure by which it may be substantially com-

pletely enclosed within a chamber. The cover comprises a plurality of slidably and pivotally connected sections some of which uncovers the upper side of that portion of the chamber in which is received each of the hoisting units as they are either individually or simultaneously moved into and out of the chamber, and which covers the upper side of the chamber while either or both hoisting units are in their elevated and in their contracted positions respectively. The sections of the cover structure are so constructed and arranged and associated with respect to each other as to be operable to open and closed positions by engagement with respective portions of the boom structures and without the aid of complicated operating means in addition to that which is required for operation of the hoisting units.

In Fig. 1 of the drawings is illustrated hoisting apparatus embodying the invention which comprises hoisting units A and B each of which are substantially identical, the description of one of which will serve, in all but certain respects hereinafter specified, for the others. These hoisting units are particularly constructed to lift vehicles but may be readily adapted to the lifting of numerous other articles. They are preferably operatively mounted on a track comprising spaced rails 10 and 11 of channel shaped cross section having inwardly facing upper flanges 12 and 13 and lower flanges 14 and 15. The rails 10 and 11 may be mounted in a shallow groove formed in a platform structure (not shown) which may be disposed upon a floor structure or they may be mounted in a shallow groove (not shown) of a floor structure with the upper flanges 12 and 13 flush with the floor surface.

The hoisting units A and B each include a shiftable carriage, generally designated in Figs. 2 and 3 by the numeral 17, having a horizontal base plate 18 and a vertically upstanding flange 19. Provided on each of the opposite ends of the shiftable carriage are wheels 20 and 21 which are received between the flanges 12 and 14 and 13 and 15 of the rails 10 and 11, respectively. The wheels 20 and 21 are journaled on the outer end portions of trunnions 22 and 23, which are respectively mounted on and extend outwardly from end flanges 24 and 25 of the carriage 17. The end flanges 24 and 25 may be welded to or formed integral with the base plate 18 and flange 19 of the carriage 17.

Each hoisting unit includes a boom member, generally designated by the numeral 29, which comprises a pair of channel members 30 and 31 having outwardly facing web portions and provided with solid lower end portions 30' and 31', respectively. The solid lower end 30' of the channel member 30 is apertured and journaled on the trunnion 22 at a location between the wheel 20 and end flange 24, as shown in Fig. 4. The solid lower end 31' of the channel member 31 is apertured and journaled on the trunnion 23 at a location between the wheel 21 and the end flange 25.

Hoisting unit A is provided with a load receiving seat, generally designated by the numeral 36, which includes a channel bar 37 on each of the opposite ends of which is pivotally mounted a rest 38 having a notch in its upper side for receiving the rear axle of a vehicle. Extending downwardly from the ends of the bar 37 are ears 39 by which the seat 36 is pivotally mounted on the channel members 30 and 31, with the aid of pins 40.

A somewhat different load receiving seat gen-

erally designated by the numeral 36', is pivotally mounted on the upper ends of the channel members 30 and 31 of the hoisting unit B, as illustrated in Fig. 1. The load receiving seat 36' comprises a channel bar 37' on each of the opposite end portions of which is shiftable mounted for movement longitudinally and transversely of the bar 37', a rubber pad 38'. Provided on the opposite side of the bar 37' are spaced downwardly extending ears 39' for receiving pins 40' by which the seat 36' is pivotally mounted on the upper ends of the channel members 30 and 31.

When the boom member of hoisting unit A comprising the channel members 30 and 31 is in its uppermost position, the lower side of the bar 37 seats upon the upper extremities of the channel members. During movement of the boom member 29 from its lower to its upper position the seat 36 is retained in a substantially horizontal position by parallelogram mechanism including link members 41 extending substantially parallel to the channel members 30 and 31 which are pivotally attached at their upper ends by a pin 42 to rigid arms 43 extending from the lower sides of the bars 37 of the seat members, as shown in Fig. 1. The lower ends of the links 41 are pivotally attached by pins 44 carried by ears 44' extending leftwardly from the flange portion 18 of the carriage 17. The pivotal axis provided by the pins 42 and 44 are equidistant from the pivotal axis of the seat 36 provided by the pins 40 and the pivotal axis of the boom member provided by the trunnions 22 and 23, respectively. This provides a parallelogram mechanism which retains and supports the seat 36 in horizontal load supporting position during movement of the boom member 29 between its lower and upper positions. When the boom member is in its upright position the seat 36 is supported in horizontal position by engagement of its lower side with the upper extremities of the channel members 30 and 31. The same parallelogram mechanism is provided in hoisting unit B and designated by the same numerals.

The boom member 29 is supported and guided during its movements by a lever system, generally designated by the numeral 45, which includes a rigid yoke element comprising an intermediate span part 46 and spaced rigidly connected link arms 47. The span part 46 and link arms 47 may be integrally formed, welded or otherwise suitably rigidly connected. The free ends of the link arms 47 are journaled on trunnions 48 fixed to and extending inwardly from the bars 30 and 31 of the boom member 29 at aligned locations intermediate the length of the bars 30 and 31. Provided on the span part 46 of the yoke are spaced bearings on which are journaled the upper end portions of a pair of levers 50. As shown in Fig. 1 the levers 50 are straight throughout the major portions of their length but are provided with slightly upwardly curved upper end portions. The lower ends of the levers 50 are pivotally attached to a cross bar 51 which extends between the rails 10 and 11 of the track structure. This cross bar is provided with upwardly extending shoes 52, one of which is engaged between the flanges 12 and 14 of the rail 10 and the other of which is engaged between the flanges 13 and 15 of the rail 11. The cross bar 51 includes integral upwardly extending pairs of flanges 53 and 54 and a central bearing portion 55 having a bore 56. The lower end of one lever 50 is received between the flanges 53 and pivotally attached thereto by a pin 57 and the lower end of the other lever 50 is received be-

tween the flanges 54 and pivotally attached thereto by a pin 58. The cross bar 51 is preferably releasably fixed to the side rails 10 and 11 by pins 59 or other suitable means such as bolts, cap-screws and the like. The bars 30 and 31 of the boom 29 are adapted to be received between the shoes 52 and the adjacent flanges 53 and 54 respectively when the hoist is in its lower position.

The hoisting unit B is substantially identical to the hoisting member A and similar parts are designated by the same numeral. However, the lower ends of the levers 50 of the hoisting unit B are pivotally attached to a cross bar 51', shown in Fig. 3, which is substantially identical to the cross bar 51 of unit A. Provided on the cross bar 51' are pairs of upstanding flanges 63 and 64. The lower end of one lever 50 is received between the flanges 63 and pivotally attached thereto by a pin 65 and the lower end of the other lever 50 is received between the flanges 64 and pivotally attached thereto by a pin 66. The cross bar 51' has an upstanding side flange 67 extending along its left side, as viewed in Fig. 3, on the left side surface of which is provided spaced pairs of ears 68. Between each pair of ears 68 is pivotally mounted a dog 69 which is engageable between teeth of a rack 70, one of which is stationarily mounted adjacent each rail 10 and 11, respectively. The dogs 69 are connected together by a bar 71 by which they may be simultaneously pivoted out of engagement with the rack 70 when it is desired to release hoisting unit B for movement relative to hoisting unit A. In this way the apparatus may be conditioned for shifting loads of different lengths.

As each boom member 29 approaches its lower position, the links 50 and arms 47 reach the relative positions shown in Fig. 13 and further lowering movement brings these members into approaching alignment. A spring 93' is tensioned during movement of the levers 50 and links 47 towards an aligned condition. This spring, shown in Fig. 15, serves to shift the levers out of alignment when the boom members are raised.

The driving apparatus by which the boom members 29 of the hoisting units A and B may be simultaneously positively raised and lowered and by which only the boom member of the hoisting unit B may be operated if desired, comprises a pair of aligned screw elements 73 and 74, associated with the hoisting units A and B, respectively. The screw element 73 is journaled at one end in the bore 56 of the bearing portion 55 on the cross member 51 and it is held against axial movement by thrust resisting collars 75 fixed to the screw 73 which engage thrust bearings 76 mounted in opposite extremities of the bearing portion 55. The other end of the screw element 73 is journaled in a bore formed in a cross member 76 which extends between and is fixed to the rails 10 and 11. The screw element 74 is journaled at one end in a bearing 77 mounted on a cross member 78 which connects the rails 10 and 11 and at its other end in a bearing 79 mounted on a cross member 80 which joins the right end portions of the rails 10 and 11.

The adjacent ends of the screw elements 73 and 74 are disengageably connected together by a clutch, generally designated by the numeral 81, which includes a clutch element 82 fixed to the right end of the screw element 73, as viewed in Figs. 1 and 3, and a shiftable clutch element 83 which is splined on the left end of the screw element 74. The clutch element 83 is provided with an operating lever 84 which is pivotally mounted at 85 on the rail 10 and operatively con-

nected at its intermediate portion to the clutch element 83. The intermediate portion of the lever 84 is enlarged and provided with an opening in which the right end portion of the clutch element is received. The lever 84 is pivotally connected with a slit ring 84' seated in a groove 85' formed in the clutch element 83, by pins 86' which loosely fits in apertures formed in the lever 84. The free end of the lever 84 extends through a slot in the rail 11 and may be rotated manually in a clockwise direction, as viewed in Fig. 3, to engage the clutch elements 82 and 83 and in a counterclockwise direction to disengage them. The carriage 17 of each hoisting unit A and B, respectively, is provided with a nut member 86 in which one of the screw elements 73 and 74 are threaded. The screw elements 73 and 74 may be driven in respectively opposite directions by a reversible motor 87 which is drivingly connected with the right end of the screw element 74, as viewed in Fig. 1. The motor and hoisting apparatus may be provided with a control circuit such as shown in my application, Serial No. 58,219, if desired.

The motor 87 may be driven in one direction to simultaneously raise the boom members of hoisting units A and B when the clutch 81 is engaged or to raise only the boom member of hoisting unit B when the clutch 81 is disengaged. The motor 87 may be likewise driven in an opposite direction to lower the boom members.

The cover structure embodying the invention is shown in Fig. 6 in its closed position with both hoisting units A and B in their lower positions and only the load receiving seat structures 36 and 36' thereof remaining above the cover structure. As viewed in Fig. 6, the cover structure includes a plate 100, located at the left of the hoisting apparatus, which is provided with slots 101 in which are received the levers 50 of hoisting unit A when it is in its upper position. The plate 100 is preferably fixed by screws or other suitable means to the rails 10 and 11 and the next adjacent plate 102, appearing in Fig. 1, is seated upon the rails 10 and 11 and fixed to the carriage 17 in order to travel therewith during its shifting movement. The plate 102 is disposed adjacent the plate 100 when the hoisting apparatus is in its elevated position but is shifted rightwardly, as viewed in the drawings, as the boom members 29 are lowered. Immediately to the right of the position in which the plate 102 is disposed when the boom members are elevated, are three successive pivotally attached plates 103, 104 and 105, respectively. The adjacent ends of the plates 103 and 104 are pivotally connected together by hinges 106 and the adjacent ends of the plates 104 and 105 are pivotally connected together by hinges 107. The left end of the plate 103 is free and the right end of the plate 105 is guided for shiftable movement longitudinally of the track by cleats 108.

A plate 109 is disposed on the top of rails 10 and 11 with its left end portion in overlapping relationship with respect to the right end portion of the plate 105 and it is guided by the cleats 108. The right end of the plate 109 is provided with slots 110, similar to the slots 101, of the plate 100, for receiving the levers 50 of the hoisting unit B. It will be seen in Fig. 1, that a plate 111, similar to the plate 102, is fixed to the carriage 17 of the hoisting unit B and slidably seated on the top of the rails 10 and 11. The right end portion of the plate 111 is disposed beneath the

left end portion of a plate 112 which is pivotally attached at its right end to the next successive plate 113 by hinges 114 which is in turn pivotally attached to the second from the last rightward plate 115 by hinges 116. The last rightwardly positioned plate 117 overlaps the main length of the plate 115 and is pivotally attached at its right end to the end of the track by hinges 118. The longitudinal marginal portions of the last rightwardly positioned plate 117 are provided with spaced apertures 119 in which pins 120, extending upwardly from the second from the last plate 115 are receivable. The last plate 117 is adapted to be pivoted upwardly about the hinges 118 to disengage the pins 120 from the holes 119 and while the plate 117 is so held the hoisting unit B may be shifted relative to the hoisting unit A to adapt the hoisting apparatus for lifting vehicles of different lengths, which vehicles may be designated by dimensions or names, not shown, on the top side of the plate 117, in associated relationship to the holes 119. The hoisting unit B may be shifted by power, as set forth in my copending application, Serial No. 58,219, this being accomplished by disengaging the clutch 81 and suitably propelling the screw 74 by the motor 87, while the hoisting units are in their lower positions.

Pivotedly mounted on each carriage 17 of the respective hoisting units A and B, is a guide bar 121 which is connected to the carriage structure at its right end by a hinge 122. The guide bar 121 comprises a flat strip of metal and its free end portion extends beyond the yoke 46 and rests upon it. During initial stages of upward shifting action of the hoisting apparatus, the link arms 47 and yoke 46 are shifted to the positions shown in Fig. 13 in which the links 47 are disposed vertically and at right angles to the levers 50 with which they are associated. A stop 123 on the bar 31 and 39 of the boom structure limits pivotal movement of the link arms 47, as shown in Fig. 13. This upward movement of the levers 47 and yoke 46 rotates the guide bar 121 in a clockwise direction and elevates the hinged edges of the cover plates 103 and 104 as illustrated in Fig. 7. During subsequent upward movement of the boom member, the guide bar 121 shifts the cover plates 103 and 104 upwardly through the progressive stages shown in Figs. 8 and 9. Further upward movement of the boom member allows the plates 103 and 104 to progressively slide downwardly upon the guide bar 121 through the stages shown in Figs. 10, 11 and 12 until they are returned to horizontal position upon the rails 11 and 12 when the boom member is in its uppermost position as shown in Fig. 1. The reverse action of the plates 103 and 104 takes place during lowering of the boom member, the guide bar 121 serving to shift the plates 103 and 104 upwardly to uncover the space between the rails 11 and 12 for receiving the boom member, and to guide the plates 103 and 104 back to their horizontal covering positions after the boom member is disposed in the space between the rails.

The same action takes place in the operation of the cover structure of hoisting unit B, in which case the guide bar 121 thereof operates the plates 112 and 113 in the same manner as the plates 103 and 104 are manipulated by the guide bar 121 of hoisting unit A. In each case, when the yoke 46 is shifted by the link arms 47 to the various positions established by the stops 123 on the boom bars 30 and 31, and stops 124 on the levers

50, the guide bar 121 follows the yoke 46 and remains in contact with it.

The foregoing cover structure therefore is automatically operable without attention of the operator and it covers the hoisting apparatus when it is in its lowered position and covers the chamber in which the hoisting apparatus is stored when the latter is elevated.

Although but one specific embodiment of the invention is herein shown and described, it will be understood that various changes in the details and construction thereof may be made without departing from the spirit and scope of my invention.

15 I claim:

1. Hoisting apparatus comprising a base portion having a recess therein provided with an open top side portion, a boom member shiftable through said open top side portion from a lower position mainly within said recess to an elevated position exterior of said recess, and a cover normally closing said open top side portion of said recess comprising pivotally connected plates engageable by said boom member and swingable relative to each other by the raising and lowering action thereof to uncover said open top side portion of said recess during movement of said boom member both into and out of said recess.

2. Hoisting apparatus comprising a base portion having a recess therein provided with an open top side portion, a boom member shiftable through said open top side portion from a lower position mainly within said recess to an elevated position exterior of said recess, a cover member for normally closing said open top side portion of said recess comprising pivotally connected plates, and guide means on said boom member engageable with said plates for swingably shifting them by the lowering and raising actions of said boom member to uncover said open top side of said recess in timed relation to movement of said boom member both into and out of said recess respectively.

3. Hoisting apparatus comprising a base portion having a recess therein provided with an open top side portion, a boom member shiftable through said open top side portion from a lower position mainly within said recess to an elevated position exterior of said recess, a lever system swingably connected with said boom member for guiding it to its upper and lower positions, said lever system being receivable in said recess and swingable through said open top side portion thereof to a position externally of said recess, and a cover member normally closing said open top side of said recess comprising cover sections shiftable relative to each other and to said base portion by the action of and in timed relationship with respect to the action of said boom member and lever system for uncovering said open top side portion of said recess during movement of said boom member both into and out of said recess respectively.

4. Hoisting apparatus comprising a base portion having a recess therein provided with an open top side portion, a boom member shiftable through said open top side portion from a lower position mainly within said recess to an elevated position exterior of said recess, a lever system swingably connected with said boom member for guiding it to its upper and lower positions, said lever system being receivable in said recess and swingable through said open top side portion thereof to a position externally of said recess, a cover member normally closing said open top

side of said recess comprising a fixed end cover section, first and second cover sections pivotally connected together at their adjacent extremities and swingable relative to each other to accommodate passage of said boom member and lever system into and out of said recess and a third cover section slidably mounted on said base portion and pivotally connected with the other extremity of said second cover section, and means on said base portion for guiding said third cover section.

5. Hoisting apparatus comprising a base portion having a recess therein provided with an open top side portion, a boom member shiftable through said open top side portion from a lower position mainly within said recess to an elevated position exterior of said recess, a lever system swingably connected with said boom member for guiding it to its upper and lower positions, said lever system being receivable in said recess and swingable through said open top side portion thereof to a position externally of said recess, a cover member normally closing said open top side of said recess comprising a fixed end cover section, first and second cover sections pivotally connected together at their adjacent extremities and swingable relative to each other to accommodate passage of said boom member and lever system into and out of said recess and a third cover section slidably mounted on said base portion and pivotally connected with the other extremity of said second cover section, and a guide element on said boom member shiftable by the action of said lever system for controlling the relative pivotal movement of said first and second pivoted cover sections to both cover and uncover said recess.

6. Hoisting apparatus comprising a base portion having a recess therein provided with an open top side portion, a boom member shiftable through said open top side portion from a lower position mainly within said recess to an elevated position exterior of said recess, a lever system swingably connected with said boom member for guiding it to its upper and lower positions, said lever system being receivable in said recess and swingable through said open top side portion thereof to a position externally of said recess, a cover member normally closing said open top side of said recess comprising a fixed end cover section, first and second cover sections pivotally connected together at their adjacent extremities and swingable relative to each other to accommodate passage of said boom member and lever system into and out of said recess and a third cover section slidably mounted on said base portion and pivotally connected with the other extremity of said second cover section, a guide element on said boom member shiftable by the action of said lever system for controlling the relative pivotal movement of said first and second pivoted cover sections to both cover and uncover said recess, and means on said base portion for guiding said third cover section.

7. Hoisting apparatus comprising a base portion having a recess therein provided with an open top side portion, a pair of relatively shiftable hoisting units each comprising a boom member shiftable through said open top side portion from a lower position mainly within said recess to an elevated position exterior of said recess, a cover member for normally closing said open top side portion of said recess comprising a pair of cover units one associated with each of said hoisting units respectively and each cover unit

including a plurality of longitudinally aligned cover plates, adjacent end portions of the adjacent cover plates of said respective units being relatively shiftably disposed in superimposed and overlapping relation for accommodating relative shifting of said hoisting units, hinge means pivotally connecting the adjacent end portions of the successive cover plates of said cover units to each other, and means on each of said hoisting units engageable with the pivotally connected cover plates of each cover unit respectively for shifting them to open position as said boom members are individually or simultaneously raised out of and into said recess respectively.

8. Hoisting apparatus comprising a base portion having a recess therein provided with an open top side portion, a pair of relatively shiftable hoisting units each comprising a boom member shiftable through said open top side portion from a lower position mainly within said recess to an elevated position exterior of said recess, a cover member for normally closing said open top side portion of said recess comprising a pair of cover units one associated with each of said hoisting units respectively and each cover unit including a plurality of longitudinally aligned cover plates, adjacent end portions of the adjacent cover plates of said respective units being relatively shiftably disposed in superimposed and overlapping relation for accommodating relative shifting of said hoisting units, hinge means pivotally connecting the adjacent end portions of the successive cover plates of said cover units to each other, and means on each of said hoisting units engageable with the pivotally connected cover plates of each cover unit respectively for shifting them to open position as said boom members are individually or simultaneously raised out of and into said recess respectively.

40 9. Hoisting apparatus comprising a base portion having a recess therein provided with an open top side portion, a boom member shiftable through said open top side portion from a lower position mainly within said recess to an elevated position exterior of said recess, apparatus for shifting said boom member between said positions including a lever element pivotally connected at one end to said base portion and a link member pivotally connected at one end to the other end of said lever and pivotally connected at its opposite end to said boom member, said link and lever members being angularly shiftable from an aligned relationship to an angular relationship while said boom member is disposed in said recess, a cover normally closing said open top side of said recess including a plurality of aligned pivotally connected plates, the pivotal connections between one pair of said plates being located adjacent said pivotally connected ends of said link and lever members for accommodating shifting of said link and lever members to said angular relationship, and a guide element on said boom member engageable with said pair of plates and shiftable by said link member for spacing said plates from said boom member during initial raising and final lowering of said boom member, said guide member being adapted to guide said pair of plates to closed position during final upward and final downward movements of said boom member respectively.

10. Hoisting apparatus comprising a base portion having a recess therein provided with an open top side portion, a boom member shiftable through said open top side portion from a lower position mainly within said recess to an elevated position exterior of said recess, load receiving seat structure on one end of said boom member, a carriage pivotally connected with the other end of said boom member and shiftably mounted on said base portion, apparatus for shifting said boom member between said positions including a lever element pivotally connected at one end to said base portion and a link member pivotally connected at one end to the other end of said lever and pivotally connected at its opposite end to said boom member, said link and lever members being angularly shiftable from an aligned relationship to an angular relationship while said boom member is disposed in said recess, a cover
